HOWARD W. JELLIFFE, OF CLEVELAND, OHIO

WATCH-WINDING MECHANISM

Application filed May 22, 1926. Serial No. 111,055.

This invention relates to watch winding mechanism and more particularly to mechanism more often used by jewelers, and others who manufacture and repair watches or whose duty it may be to test the accuracy of 5 watches left in their care. My invention has for its object a mechanism whereby a great number of watches may be wound successively and very quickly without exerting manual force other than that of pressing the watch 10 against the proper driving mechanism. A difficulty has arisen with regard to such devices in the past, for the reason that various watches having a great diversity of size and 15 strength of main spring, have required different power for winding them, and no means of adjustment for such disparity has to my knowledge been provided. A clutch has usually been used to drive the mechanism for 20 turning the watch stem that was pressed thereagainst, and this clutch was supported to avoid over winding, by slipping when the 25 watch was fully wound.

But if the mechanism used was provided 25 for winding watches having strong springs, it was found far too powerful for winding the smaller springs of delicate time-keepers. While it was recognized that less power was required for the smaller watches, it has here- 30 tofore been difficult to properly provide for accurate adjustment of the parts, so that the watch might be held against the driver until the latter automatically stopped rotating. A further difficulty arose from former struc- 35 tures which did not provide for winding by the same mechanism a large number of watches having stems greatly differing in size, the socket suitable for properly winding a watch having a large stem tending to drive 40 one with a small stem with greater force.

I have overcome these defects by especially 45 providing for means of adjusting the driving force of the clutch employed, so that a watch maker might divide up a large number of 50 watches to be wound into several groups according to size, and after winding those of the larger group, adjustment can readily be made for winding with equal facility the watches of another group of quite different size.

It is a further object of my invention to provide a common driving element with a plurality of socket members of different size any one of which may be easily substituted for any of the others.

These and other objects of my invention I am able to accomplish by a construction embodying the features herein described and illustrated in the accompanying drawings, in which—

Figure 1 is a side elevation of my improved mechanism in operation;

Figure 2 is a central longitudinal section of the same;

Figure 3 is a transverse sectional view of the device taken in the plane indicated by 3—3 of Fig. 1;

Figure 4 is a similar view taken in the plane indicated by the line 4—4 of Fig. 1;

Figure 5 is a sectional view of a modified form of detachable element with parts broken off, and

Figure 6 is a longitudinal section of a modified detachable plug.

My winding mechanism is mounted upon an outwardly extending driving shaft 1 from a motor 2 resting upon a base 3. This shaft is axially immovable, being mounted upon and driven by the motor 2, and is provided with longitudinal keyway 30 for a portion of its length, a threaded enlarged portion 4 upon which a nut 5 is threaded, and a reduced portion 6 providing a shoulder thereon 7. This nut has a knurled periphery 8 for manually adjusting it lengthwise of the shaft by rotation about the enlargement 4. A clutch member 28 having a similar shoulder 9 is mounted upon said shaft and is provided with a key 10 to permit relative movement of said member axially but fixed to the shaft for rotation therewith. A coiled pressure spring 11 is mounted upon the shoulders 7 and 9 for exerting pressure against the clutch member in a direction away from the motor. The nut 5 is provided for adjusting the force normally exerted by the said spring 11.

A sleeve 12 is mounted loosely upon the outer end of the shaft 1 and is secured against withdrawal therefrom by means of a washer 13 mounted upon a reduced end portion 14

of the shaft and seated within an enlarged cavity 15 of the said sleeve and bearing against the shoulder 16 of the sleeve. The washer 13 is retained upon the portion 14 by 5 a small ring washer 17 which is in turn secured against the end of the shaft by an axial screw 18. A small pin 19 may be inserted through the washer 13 and into the shaft to make certain the rotation of the parts together. The washer 13 being secured against 10 removal and independent rotation serves well its purpose as one of the bearings for the sleeve 12 whose shoulder 16 rotates upon the face of said washer, and its inner surface 15 upon the edges of the washer.

The rear end of the sleeve 12 opposite the shoulder 16 bears against the friction surface of the member 28 or an independent friction disc 20 carried by the said member. In any 20 case, the member 28 driven by the shaft 1 will serve as one member of a friction clutch mechanism of which the sleeve 12, mounted between parts 13 and 28, serves as the driven member which will be rotated with shaft 1 25 when the pressure between the clutch members create sufficient friction, and will rotate independently of shaft 1 when the resistance encountered by 12 is too great for the friction between the clutch members to over- 30 come.

It is a prominent feature of my structure that I may use interchangeably several winding elements 21 which are detachable readily from the sleeve 12 and parts carried by it. 35 In Figs. 2, 3 and 4, I have shown the sleeve 12 provided with longitudinal grooves 22 of which there may be a pair oppositely arranged upon the periphery of the entire length of the sleeve, and in which are located 40 flexible members 23, the rear ends being quite fixedly secured to the sleeve by screws 24, and an intermediate point of the members being attached to the sleeve by a second pair of screws 25 serving as a fulcrum to resist 45 the outward bending of the unattached ends of the springs. These ends are each bent radially inward and then outward to form V-shaped portions 26 which serve to lock in position, though detachably, the winding elements 21 which, because of the bent structure of the ends 26, may be forced inward to 50 the rear of these bent ends, as will be later more fully explained.

The form of detachable elements 21 shown 55 in Fig. 2, comprises an annular part 27 having at its rear face a reduced cylindrical portion 29 which fits in telescopic relation within the other end of the sleeve 12. The outer face of the member 27 has extended therefrom a 60 sleeve element 31 which is adapted to receive therein a sort of plug 32 which is preferably formed of some vulcanizable composition which, though slightly yieldable, may be 65 readily cemented to the inner surface of the sleeve. This plug is shown as solid in Fig.

2, and has at its outer end a conical socket for receiving therein the stem of a watch to be wound. The outer end of the sleeve 31 is provided with an enlarged and knurled portion 33 to assist the manual insertion of element 21 in the sleeve, the plug permitting manual insertion of the watch stem 35 into the socket, and by frictional engagement therewith be rotated and the watch wound. 70

A central opening 36 is provided in the annular part 27, there remaining an annular inner surface 37 within the sleeve 31 and about the opening 36, which forms a shoulder against which the rear end of the plug 32 may abut and resist undue tendency of the latter to yield under the pressure exerted by the stem 35 while being wound. It is apparent that the element 21 may readily be detached from the sleeve 12, since the flexible members 23 will yield sufficiently to permit the part 27 to be forced forwardly and, another element 21 of the same or different form substituted therefor, the members 23 returning radially to their former and normal position. 75

The form of detachable winding elements 21 so far described, disclose the same having a radial flange 38 which is held detachably within the outwardly-yielding spring arms 23. Obviously, this is not essential to retain my improved arrangement of elements for making the winding members interchangeable, but that spring members carried by the sleeve 12 on its periphery may be enclosed by portions of the winding element, when desired; and I have so shown the connection in the structure illustrated in Fig. 5, where I have provided a similar sleeve 31 mounted integrally with the socket-element 39 which has a similar central opening 40 providing a similar shoulder 47 for receiving a plug thereagainst, there being an annular flange part 48 having a rearwardly-directed cup flange 41 which is sufficiently larger than the outer surface of the sleeve 42 to provide a slight annular space 43 therebetween to receive a pair of spring elements 44 (only the forward ends of the arms being shown), there being longitudinal slots 45 in the flange 41 and sleeve 42 in which the arms 44 neatly fit and thereby permit the sleeve 42 and socket member 39 to rotate together. These slots 45 on the internal surface of 41 serve the same purpose as and correspond to the longitudinal slots 51 in the flange 38 of the other form. In the latter case, the springs 23 fit into such slots, as shown more clearly in Fig. 1. 100

The springs 44 exert a normal pressure outwardly tending to fit into the slots 45. This is just opposite to that of the arms 23 which tend to move inwardly into the slots 51. Spring arms 44 may be secured to the sleeve 42 in any suitable manner, as by screws, in the manner that the arms 23 are secured to 105 110 115 120 125 130

the sleeve 12 in the other form, though it is clear that but one pair of screws will be needed in the attachment of the arms 44. The sleeve 31 is used in either form of detachable winder element. The socket in the sleeve 31 as shown in Fig. 5, may receive the plug of slightly yieldable material, as before explained.

It will now be shown that other forms of such winding plugs may be used in either form of winding element 21 or 39. In Fig. 6, I have shown a perforated plug 50 whose general outline is much like that of the plug 32, but which is provided with a smaller socket 52, leaving a flat annular surface 53 on the end of this plug. This form of plug is especially adaptable for winding small wrist watches, and without straining them by exerting manually too great pressure on their stems. The perforation 54 in this plug 50 is axial thereof and in alinement with the socket 52. It will be understood that there is always a gradual wear of the surface of the socket against which the stem is pressed, especially when the plug is driven by power, as in this case, and that it is highly desirable that the winding contact should be at a surface as far removed from the center of the stem as possible, and this is especially true when the knurled stem is so small as in wrist watches. The aperture 54 meets this condition very nicely by offering no resistance to the stem at its axial center, but presents a wedging action at the socket about the opening 54.

As the cushion socket gradually recedes from the plug end by the wear therein, the watch stem will fit as well as ever in the socket, and there will not result any central resistance by the perforated socket, as it gradually increases in the use of the conical socket shown in Figs. 1 and 2. The plugs 32 and 50 may be used in either type of winding element, though the plug selected is usually retained in the socket of sleeve 31 which is selected, since the plug is cemented therein quite securely, and with my type of detachable winding element there may be provided a number of the preferred winding elements each having a plug with a different size socket, and some of the plugs having the perforation 54 and some solid. It is to be understood that I contemplate using either type of plug with either type of winding element, and that there may be a series of winding elements each having different types of plugs or plugs of the same type but having different size sockets. My improved mechanism enables very ready detachment of one winding element and substitution of another of the type and size desired. All this can be done without making any change in the structure of the sleeve 12 or 42 and clutch therefor, or parts rearward from such sleeve.

65 *Operation.*—Only the shaft 1 need be

mounted upon the motor 2. All other parts are interchangeable for repair or replacing with new parts. In assembling the mechanism, the part 5 is first screwed into place quite far back on the body 4. The spring 11 is then applied upon the shoulder 7, after which the clutch member 28 is slipped over the shaft and keyed thereon. Now, either of the sleeves 12 or 42 is mounted rotatably upon the shaft 1, after which the washer 13 is applied to lock the sleeve against forward axial movement on the shaft, the washer being pinned by 19 against independent rotation on the shaft. After the washer 17 is attached, the screw 18 secures the parts 13 and 12 in position, though the selected sleeve 12 or 42 may move rearward axially on the shaft when pressure is applied to the plug.

The entire mechanism therefore comprises an axially immovable but rotatable driving shaft with a clutch thereon including therein a spring which tends to produce contact of the clutch elements, but which is so arranged that the frictional contact of its elements is increased by pressure of the watch stem on the plug carried by the driven element of the clutch, since the stem will be driven rotatably by holding the watch in the hand, and pressing the stem 35 against some sort of driven plug, such as plug 32. The same mechanism may readily be equipped with either of the winding elements 21 or 39, and with either of the sleeves 12 or 42 for receiving thereon such winding elements. Further, any one of the winding elements may be equipped with either of the types of socket plugs, and a machine will ordinarily be intended to receive thereon one of a series of such winding elements detachably.

I have therefore invented a novel and useful winding mechanism which will rapidly wind watches of widely different character by power, and with sensitive adjustment as to the power required to fully wind the same, depending upon the delicacy of the main spring of the individual watch, and yet having quite positive limits beyond which force applied by the motor will not be exerted to the injury of the watch.

Having fully described my invention, what I claim as new, and desire to secure by Letters Patent of the United States, is—

1. In a watch winding mechanism, the combination of an axially immovable drive shaft, friction clutch elements mounted on said shaft and movable axially thereon, the driving element being keyed to the shaft and the driven element being loose thereon but held by said shaft against movement away from the keyed element beyond certain limits, a shouldered nut threaded on said shaft adjacent the driving element of the clutch, a pressure spring element mounted between the shoulder and the keyed element for normally holding the clutch in engagement, the said

driven element having an annular portion projecting beyond the limits of the shaft, a winding element for detachably engaging said projecting portion, and having means for receiving yieldably thereagainst the stem 5 of a watch to be wound, and power means for rotating said drive shaft.

2. In a watch winding mechanism having a power-driven but axially immovable shaft, a clutch slidably mounted bodily on said shaft 10 and means for normally pressing the members of said clutch into axially engaged relation, a winding element for detachable engagement with the driven element of the clutch comprising an apertured portion having an annular flange, an integral sleeve portion extending in alinement with said aperture and away from said flange, and a socketed plug of elastic material cemented within 15 said sleeve portion and having a socket at the outer end thereof to receive therein the axial pressure of the stem of a watch to be wound.

3. The combination in a watch winding mechanism of a rotatable and power-driven, 20 but axially immovable drive shaft, clutch elements mounted upon said shaft, the driving element of the clutch being keyed to the shaft but the driven element loose thereon, yielding means pressing against the driving element for normally holding said clutch elements in clutched relation, the said driven element having a portion projecting away from the clutch and beyond the limits of the shaft, and a winding socket element 25 connected with said projecting portion for receiving therein the stem of a watch to be wound.

4. The combination in a watch winding mechanism of a rotatable and power-driven, 30 but axially immovable drive shaft, clutch elements mounted upon said shaft, the driving element of the clutch being keyed to the shaft but the driven element loose thereon, a coil 35 spring encircling said shaft and pressing against the driving clutch element for normally holding said elements in clutched relation, the said driven element having an annular portion projecting beyond the limits of the shaft, and a winding socket element 40 detachably connected with said annular projecting portion for receiving therein the stem of a watch to be wound.

5. The combination in a watch winding mechanism of a rotatable and power-driven, 45 but axially immovable drive shaft, clutch elements mounted upon said shaft, the driving element of the clutch being keyed to the shaft but the driven element loose thereon, 50 yielding means mounted upon said shaft at one end thereof for normally holding said clutch elements in engaged relation, but permitting bodily movement of the clutch longitudinally of the shaft, and a winding socket 55 element for detachable engagement with said

driven element adjacent the opposite end of the shaft, for receiving therein the stem of a watch to be wound.

6. The combination in a watch winding mechanism of a rotatable and power-driven, 60 but axially immovable drive shaft, clutch elements mounted contiguously upon said shaft, the driving element of said clutch being keyed to the shaft but the driven element loose thereon, a spring member mounted upon one end of said shaft and tending to hold the clutch elements in engaged relation but yielding to permit bodily movement of the clutch longitudinal of the shaft, a winding socket element for detachable engagement with said 65 driven element adjacent the opposite end of said shaft for receiving therein the stem of a watch to be wound, and means on said shaft at the rear of said spring for adjusting the force exerted by said spring member.

7. The combination in a watch winding mechanism of a rotatable and power-driven, 70 but axially immovable drive shaft, friction elements mounted upon said shaft, the driving element of said clutch being keyed to the shaft but the driven element loose thereon, a coil spring encircling one end of said shaft and exerting pressure against said keyed clutch element to hold the clutch elements 75 normally in an engagement, a stop nut threaded upon said shaft end bearing the said coil spring for adjusting the clutch pressure normally exerted by said spring, a winding socket element mounted in engagement with said driven element adjacent the end of said shaft 80 opposite the coil spring for winding a watch whose stem is pressed axially against said winding element, and opposing the pressure of said coil spring.

8. In a watch winding mechanism, the combination of an axially immovable power shaft, friction clutch elements mounted on said shaft and movable axially thereon, the driving element being keyed to the shaft and the driven element being loose thereon but held by said shaft against movement away from the keyed element beyond certain limits, a nut threaded on said shaft adjacent the driving element of the clutch, a pressure spring mounted between the nut and the keyed element for holding the clutch elements normally in engagement, the said driven element having a projecting portion extending beyond the end of the shaft, a winding element 95 for detachably engaging said projecting portion, and having elastic means for receiving thereagainst the stem of a watch to be wound.

In witness whereof I have hereunto set my hand this 20th day of May, 1926.

HOWARD W. JELLIFFE.
